UNITED STATES PATENT OFFICE.

WILLIAM THOMAS CRAVEN, OF ILKLEY, LEWIS JACKSON CRAVEN, OF LEEDS, CHARLES HENRY YOUNG, OF BRIGHOUSE, FRANK HORATIO CLIFFE, OF HIPPERHOLME, AND WILLIAM STEAD CLIFFE, OF LONDON, ENGLAND.

APPARATUS FOR MERCERIZING COTTON PIECE GOODS AND THE LIKE.

1,165,570.

Specification of Letters Patent. Patented Dec. 28, 1915.

Application filed April 7, 1913. Serial No. 759,532.

To all whom it may concern:

Be it known that we, WILLIAM THOMAS CRAVEN, LEWIS JACKSON CRAVEN, CHARLES HENRY YOUNG, FRANK HORATIO CLIFFE, and 5 WILLIAM STEAD CLIFFE, subjects of the King of Great Britain, residing, respectively, at Ilkley, Leeds, Brighouse, Hipperholme, and London, in the county of London, England, have invented new and useful Improvements 10 in Apparatus for Mercerizing Cotton Piece Goods and the like, of which the following is a specification.

This invention relates to mercerizing machinery, and the object of our invention is 15 to construct a machine which will take up less room than the present mercerizing ranges, one that can be run one, double, or more drafts, is more easy to manage, and by improved means for holding the cloth 20 tight on the rollers dispense with the clips and pins hitherto employed, obtain a better finish, and prevent the cloth piping, or any waste of caustic soda.

According to our invention the cloth is 25 sues from the customary tensioning and breadthening devices, and passes under a guide roller to a caustic soda solution or bath within a tank or cistern. The cloth is passed through the solution by means of 30 a series of guide rollers and nip rollers. The guide rollers are partially immersed in the caustic solution while each nip roller has a rubber or suitable elastic periphery and rests between and in contact with two of the guide 35 rollers in such a manner that the whole surface of the cloth is in contact with one or the other of these rollers. Before entering the caustic bath however the cloth or web passes over an extra nip roller resting upon 40 the first guide roller, and then passes under and over respectively the guide rollers and nip rollers throughout this series.

Adjoining the caustic bath or tank is a 45 second tank which is steam heated and sur- mounted by a second series of iron rollers and elastic surfaced nip rollers, where the caustic solution is partially washed off the cloth preferably by a number of jets or sprays of water playing thereon near the 50 nip of the first two or more pairs of rollers. Also a pressure roller rests upon the cloth as it passes over the nip roller situated between the two tanks.

In order to counteract any possibility of

shrinkage in the cloth under treatment several of the nip and guide rollers in the second tank are corrugated or grooved with the concavities in one set of rollers more or less meshing with or arranged opposite the convexities in the adjoining or succeeding set of rollers so that in passing under and over these rollers the cloth is stretched laterally and at varying points throughout its width, the pressure being adjusted as desired. Two grooved guide rollers are employed to each 65 grooved nip roller, and in this case the cloth passes over the guide rollers and under the nip rollers, but before passing to the second or last pair of guide rollers the cloth passes under an intermediate guide roller which 70 enables the second set of rollers to operate upon precisely the same surfaces as the first set. After leaving these grooved rollers the cloth passes under an intermediate roller and over and under two large tension cylinders with roughened surfaces also within this tank, and then between a further pair 75 of nip and guide rollers and over another guide roller. From this roller the cloth passes over and under a series of rollers 80 fixed within a compartment in a third tank where the caustic solution is wholly washed out or removed. Upon leaving this compartment the cloth now passes between a second pair of nip and guide rollers, the nip 85 roller having an elastic surface as before described, to a further compartment in said tank. A jet or spray of water playing on the cloth as it enters the nip of these last pair of rollers effectually removes any trace 90 of caustic soda solution there may be left.

The second compartment in the third tank contains an acid bath and the cloth after being passed through this bath is passed between a further elastic surfaced nip roller 95 and an ebonite surfaced guide roller and then passes to a third compartment containing clear water where it is finally washed. After having the superfluous moisture or water extracted by being again subjected to 100 the action of another pair of elastic and ebonite surfaced rollers it passes to an ordinary plaiting down device.

Description of drawings.—Figure 1 is a side elevation of part of our improved mercerizing range. Fig. 2 is a plan view of Fig. 1 showing means for operating same, and cloth being run double draft. Figs. 3, 3^A, are

continuations of Fig. 1. Figs. 4, 4^A, are plan views of Figs. 3, 3^A.

Similar figures refer to similar parts throughout the several views.

- 5 The cloth or web A is introduced to our improved machine by being passed over and under the customary tensioning and broadening devices 1 and 2 respectively to a guide roller 3 and then over and under a series of 10 rollers 4, 5. These rollers are supported in bearings 6 at each side of a tank or cistern 7 containing a caustic soda solution, and are driven by bevel gear 8 from a side shaft 9 operated by gear wheel 10 driven by pinion 15 11 on engine crank shaft, or from any other suitable source. The bottom or guide rollers 5 are composed preferably of cast iron and are partially immersed in the caustic soda bath, while the nip rollers 4 have india rubber or other suitable elastic covered peripheries 12 and are carried in adjustable bearings 13, pressure being regulated by the screw 14 and hand wheel 15. A nip roller 4 rests in contact with and between two of the 20 guide rollers 5 in such a manner that the web in passing under and over these rollers is held in contact with same over its whole surface. One of these nip rollers similarly mounted rests upon the first of the guide 25 rollers and the web A passes over this roller before entering the caustic bath.

Adjoining the tank or cistern 7 is a second tank 16 which is steam heated and also surmounted by a second series of nip and 30 guide rollers 4, 5 regulated and driven as before described, where the caustic solution is partly washed off the web in its passage by means of preferably a number of jets or sprays of hot water or the like from the 35 pipes 17 playing on the same near the nip of the first two or more rollers 4 on entering the tank 16. Further an iron pressure roller 18 bears upon the web as it passes over the nip roller 4 situated between the tanks aforesaid. The pressure of this roller 18 is regulated by screw and hand wheel as before 40 mentioned.

In order to counteract any possible shrinkage in the cloth under treatment several of the nip and guide rollers in the tank 16 are provided with corrugations or annular grooves 19, and the corrugations or the like in each set of nip and guide rollers are so arranged that the concavities 45 in one set more or less mesh with or are opposite the convexities in the adjacent or succeeding set. The webs are thereby stretched laterally, the nip or pressure occurring in varying positions across their 50 entire width and is regulated by the means before described. Where an extra wide web or more than two webs is or are to be treated, the corrugations in these rollers will require to be formed upon the whole of their surfaces 55 so as to operate over the whole width of

said web or webs. Two sets of two corrugated guide rollers and one corrugated nip or pressure roller are preferably employed herein and the webs in traversing these corrugated rollers preferably pass over the 70 guide rollers and under the rollers 4, and in order to bring the same surface into contact with both of these nip rollers, they pass under an intermediate guide roller 20 situated between the two sets of guide rollers in 75 bearings carried by the sides of the tank. Upon leaving the last of these corrugated rollers the web or webs pass under a guide roller 21 and over and under two large tension cylinders 22, 23, with roughened surfaces, also mounted in bearings and within the tank 16. These cylinders 22, 23 take up any slack there may be in the web or counteract any tendency of the same to slip and assist it in its traverse through the machine. 80 The web or webs now pass between a further pair of nip and guide rollers and over guide roller 25 to a compartment 26 in a third tank 27 containing water where the caustic solution is wholly washed out or removed 85 from the webs. The web or webs in traversing this compartment pass under and over preferably iron guide rollers 28 and the superfluous moisture is extracted upon their leaving said compartment by passing between another pair of nip and guide rollers aforesaid on their way to a second compartment 29 containing an acid bath. A series of jets or a water spray from pipe 34 playing on the webs as they enter the nip of the 90 aforesaid rollers effectually removes any trace of the caustic solution there may be left.

The cloth upon entering the compartment 29 passes under and over preferably wood guide rollers 30 and upon leaving such compartment is again subjected to a squeezing action by a further pair of nip and guide rollers before passing to a third compartment 31 containing clean water where in 100 passing under and over a further set of wood guide rollers 32 it is finally washed. Upon leaving compartment 31 the superfluous moisture is again extracted by the web or webs being subjected to the action of another pair of nip and guide rollers as aforesaid and then passing to the customary plaiting down device 33 the process is completed. The guide rollers 5 over which the web or webs pass upon leaving compartments 29 and 31 are preferably covered with ebonite upon their peripheries. 105

110 By these means the web or webs while containing any caustic likely to cause a shrinkage is or are kept tight on the rollers 4, 5, and every part of the web or cloth is held in contact therewith by the particular arrangement of such rollers, and the tension rollers 22, 23. The web or webs is or 115 are not released from such contact until the 120

caustic soda is weakened by the sprays of hot water or weak washing from the pipes 17. Also before its release any possible shrinkage in the web while in contact with 5 the rollers 4, 5, is further counteracted or removed by the stretching influence of the corrugated section of rollers before described.

What we claim as our invention and desire to secure by Letters Patent is:

In a mercerizing apparatus the combination of a tank, a series of guide rollers in said tank, intermediate rollers designed to hold the web in uninterrupted contact with the 15 guide rollers, a second steam heated tank adjacent to the said tank, a series of corrugated guide rollers on such steam heated tank, adjustable corrugated stretching rollers adjacent to the corrugated guide rollers, 20 tensioning rollers within said tank between said stretching and guide rollers and the

end of the tank, an adjoining tank containing washing and acid compartments and squeezing rollers adjacent to the tank operating upon the web as it leaves each tank 25 or compartment, means for passing the web through the washing and acid compartments, substantially as described.

In testimony whereof we have signed our names to this specification in the presence of 30 two subscribing witnesses.
